Primary Examiner—Louis S. Zarfas*Assistant Examiner*—Robert A. Delehanty*Attorney, Agent, or Firm*—Pennie & Edmonds LLP[57] **CLAIM**

The ornamental design for a glove, as shown and described.

DESCRIPTION

FIG. 1 is a perspective view of a glove according to the invention;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken line shown in the drawing is understood to define the boundary of the claimed design and forms no part of the claimed design.
